(57) **CLAIM**

The ornamental design for a bipod with sling stud mount, as shown.

DESCRIPTION

FIG. 1 is a front, left, top perspective view of the bipod with sling stud showing our new design;
FIG. 2 is a front elevation view thereof;
FIG. 3 is a rear elevation view thereof;
FIG. 4 is a left elevation view thereof;
FIG. 5 is a right elevation view thereof;
FIG. 6 is a top elevation view thereof;
FIG. 7 is a bottom elevation view thereof; and,
FIG. 8 is a rear, left, top perspective view of the bipod in a folded configuration.

The shade lines in the Figures show contour and not surface ornamentation.

The broken lines showing portions of the design in all figures are included for the purpose of illustrating environment and do not form a part of the claimed design.

1 Claim, 7 Drawing Sheets
